(57) **CLAIM**

The ornamental design for a case for electronic communication device, as shown and described.

DESCRIPTION

FIG. 1 is a bottom front perspective view of a case for electronic communication device showing the claimed design;

FIG. 2 is a top front perspective view thereof;

FIG. 3 is a bottom rear perspective view thereof;

FIG. 4 is a bottom view thereof;

(Continued)

FIG. 5 is a top view thereof;
 FIG. 6 is a left side view thereof;
 FIG. 7 is a right side view thereof;
 FIG. 8 is a front view thereof;
 FIG. 9 is a rear view thereof;
 FIG. 10 is an enlarged top plan view of the encircled region in FIG. 2; and,
 FIG. 11 is an enlarged top plan view of the encircled region in FIG. 2.
 The dashed broken lines in the figures represent environmental subject matter, and form no part of the claimed design.
 The dot-dash broken lines are included in FIGS. 2, 10, and 11 to delineate the portion of the case for electronic communication device shown in an enlarged scale in FIGS. 10 and 11.
 The dot-dot-dash broken lines in the figures show boundaries that form no part of the claimed design.
